UNITED STATES PATENT OFFICE.

DONALD H. STEVENSON, OF GARDNER, MONTANA.

AUTOMATIC PISTOL.

Application filed August 5, 1920. Serial No. 401,416.

To all whom it may concern:

Be it known that I, DONALD H. STEVENSON, a citizen of the United States, residing at Gardner, in the county of Park and State 5 of Montana, have invented certain new and useful Improvements in Automatic Pistols; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to automatic firearms and especially to automatic pistols and has for an object to provide a weapon of this class embodying a new and improved type of breech block.

20 A further object of the invention is to provide in a weapon of this class a new and improved type of firing pin co-acting with the new and improved breech block.

A further object of the invention is to 25 provide in a weapon of this class a new and improved type of sear co-acting with the firing pin and breech block.

A further object of the invention is to provide new and improved actuating means for 30 the several organized parts, consisting of the breech block, firing pin and sear.

A further object of the invention is to provide improved safety means for maintaining the weapon against the possibility of 35 accidental discharge.

With these and other objects in view, the invention comprises certain novel parts, elements, units, combinations, mechanical movements, functions and inter-actions as disclosed in the drawings together with mechanical equivalents thereof as will be hereinafter more fully described and claimed.

The invention, in its preferred form, is clearly disclosed in the accompanying drawings, forming a part of my specification, and in which like reference characters identify corresponding parts throughout the several views. Briefly described:

Figure 1 is a view, partly in central vertical longitudinal section and partly in elevation, of my automatic fire-arm, the parts of the firing mechanism being in so-called "cocked" position;

Figure 2 is a similar view, showing the 55 position the parts assume at the extreme

limit of their movement under the influence of recoil;

Figure 3 is a similar view, showing the position of the parts at the moment of explosion;

Figure 4 is a detached detail view in side elevation of the firing-pin structure;

Figure 4^a is a perspective view of the firing pin disassociated from its accessories.

Figure 5 is a detached detail view in side elevation of the breech block;

Figure 5^a is a perspective view of the breech block removed.

Figure 6 is a fragmentary detached detail view in perspective of a portion of the safety mechanism;

Figure 7 is a fragmentary detail view in section of the sear, breech block, and of certain parts carried thereby;

Figure 8 is a detached detail view in perspective of a sear engaging member carried by the trigger;

Figure 9 is a detached fragmentary detail view in perspective of the rear portion of the barrel extension, and showing more particularly two ribs carried thereby and upon which the breech block rides during recoil;

Figure 10 is a detached detail view in perspective of one of the safety members;

Figure 11 is a detached detail view in side elevation of part of the mechanism for withdrawing the firing-pin, and compresses the firing-pin spring during recoil;

Figure 12 is a detached detail view in side elevation, partly in section, of the parts shown in Figure 11, together with certain associated parts, and showing also a portion of the breech block and firing-pin structure.

Referring now in detail to the drawings: 95
 1 designates the barrel, 2 the barrel extension, 3 the handle grip and 9 the trigger-guard of my automatic pistol. The barrel 1 is detachably secured to the barrel extension 2 in any suitable manner so that the two parts constitute a rigid unitary structure, 100 adapted to slide a slight distance (preferably three-eighths of an inch) upon the receiver 4 shown at Fig. 1. Suitable means are provided for limiting the rearward movement of the barrel 1 and its extension 2 and, in this instance, such means preferably comprise co-operating elements carried by the extension 2 and the receiver 4. In the exemplified form of such means, the forward portion 5 of the receiver 4 is recessed, as 110

shown at 6, forming a rear shoulder 7, engageable by a downward projecting lateral lip 8 on the bottom of the barrel extension 2.

The grip 3 is provided, at the bottom of 5 its front wall, with a projection 10, provided with a curved upper wall 11, conforming to the curvature of the hand of the operator. This projection functions to keep the operator's hand from slipping down, and supports 10 the bottom of the hand.

12 designates the breech block, slidably mounted at the forward end of the rear hollow shell-like portion 2' of the barrel extension 2, and adapted to open and close the 15 breech 16. The breech block is peculiarly formed and will be particularly described in connection with co-operating or associated parts.

Normally the breech block is firmly held 20 against the rear end of the barrel 1 by being wedged against the inner ends of longitudinally extending ribs 23, carried on the inner surface of the side walls of the barrel extension shell 2', the upper longitudinal edge 25 of each rib being inclined with reference to the axis of the barrel 1 in an upward direction from the inner to the outer end of the rib, said inclined edge being identified by the reference numeral 24.

30 The firing-pin, of peculiar construction, comprises the firing-pin proper, 17, a tubular member 18, having a closed end, from which said firing-pin proper projects in line with the axis of said member, and two rearward projecting arms 19, 19, having each a longitudinally extending slot 20 and a lateral rear bridge 23', connecting said arms, the member 18 carrying at its top, a projection 21, having, as shown, a front wall at 40 right angles to the axis of said member and a rear wall inclined to said first-mentioned wall. This projection 21, in the forward position of the firing-pin within the breech block 12, enters an internal recess 22 in the 45 latter. The firing-pin tubular member 18 is slideable, as usual, within the longitudinally extended recess 13 in the breech block 12. The firing-pin proper 17, in the extreme forward position thereof, projects through an 50 aperture 14 in the forward end of the breech block.

The sear of my pistol comprises an arm 25 depending, in a forward and downward curved direction, from a pivot at 26, the ends 55 of said pivot being carried by the breech block and extend through slots 20 of the arms 19, 19 of the firing-pin barrel 18 and through the sear which is substantially a bell crank lever as will be hereinafter more fully 60 described. The arm 25 has a toe 26' engaged by the extremity of the shorter arm 21', having a beveled end 21a, of a bell crank lever, fulcrumed on a pin 28, carried toward the upper end of the trigger 29, pivoted at 65 30 to the receiver 4, the extremity of the

longer arm 27 of said lever being beveled, or inclined, as shown at 31, and movable against a correspondingly inclined shoulder 32, interiorly of the barrel extension 2, toward the front end thereof. Said arm 25 70 also carries a finger 33 in advance of the toe 26' and adapted to be engaged by a safety projection, or toe, 34, angularly and laterally carried by a pin 34' angularly supported at the upper end of a bar 35, 75 more particularly hereinafter described. The sear also carries at its pivotal end a downward projecting toe 36, against which rests the head 37 of a preferably tapering pin 38, projecting into the tubular portion 18 80 of the firing-pin and encircled by the firing-pin driving spring 39, disposed, as usual, inside the tubular, or barrel, portion 18, one end of said spring bearing against the closed end of said member 18 and the other end 85 against the head 37.

The pivot at 26 also passes through the rear portion of a forward-projecting arm 40, provided with a hook-extremity 41, having a lower inclined, or beveled, edge 42, said 90 hook 41, in the cocked position of the fire-arm, engaging the projection 21 of the firing-pin tubular body 18, as shown clearly in Figure 1. Said arm 40 has a rear pendent portion 36', corresponding to, and parallel 95 with, the toe 36, the parts 25, 26, 40, 36 and 36' being united to form a rigid unitary structure, the head 37 resting against said parts 36 and 36' and moved thereby against the tension of the spring 39 as will be hereinafter more fully explained. 100

Normally disposed in cut-away portions 43 in the rear of the breech block 12 are the ends of a crosshead 44, carried at the projecting upper end of and integral or rigid 105 with a bell crank lever 45, pivoted at one end thereof, as shown at 46, to one end of a link 47, the latter being pivoted at its opposite end, as shown at 48, to ears 49, internally carried by the handle grip 3, 110 toward the upper rear end thereof. The longer arm of said bell crank lever 45 normally projects in an upward and forward direction from the pivot 46, as shown in 115 Figure 1. Said longer arm of the lever also rigidly carries, at its upper end, a member 50, formed as a beak, adapted in the recoil movement of the parts, to contact 120 against the bridge 23' of the firing-pin for a purpose which will appear in the description of the operation of the mechanism. The shorter arm of the bell crank lever 45 is provided with a hook-extremity 51, engaging one end of a stirrup 52, the other end of said stirrup engaging the hook-extremity 53 of a rod 54, carrying at its 125 other end, a head 55. Encircling the said rod 54 and bearing at one end against said head and at the other end against the upper end of a housing 56, carried at the rear of 130

the hand grip 3, is a coil spring 57. The head 55 moves and is guided in a suitable recess, or pocket, 58, formed by the housing 56.

5 The link 47 carries, at the end thereof, adjacent the pivot 48, a toe 59, engageable with a shoulder 60 on the inner surface of the rear wall of the hand grip 3, thus limiting the movement of said link in one direction.

10 Coiled around the pivot-pin 30 of the trigger 29 is a spring 61, one end of which bears against the pin 62, carried by said trigger, and the opposite end against the 15 longer arm of the bell crank lever 27, said spring tending to rock said longer arm upward.

The safety arm 35, carrying the safety projection 34, previously referred to, is 20 pivoted, toward its lower end, on a pivot-pin 63, carried by the hollow projection 10. A leaf spring 64 is coiled around said pivot pin 63 and one end thereof bears against the inner surface of the front wall of the 25 hand grip 3, and the other end against the lower portion of the arm, or bar, 35, and tends to throw said arm toward the rear of the handle grip. The bar 35 is provided with an expanded portion 65, intermediate 30 its ends, which projects rearward through an opening 66 in the rear wall of the grip 3, and is provided at its end with the angled grip portion 67, having a projection 68.

The bar 35 also carries, at a point thereon 35 above the expanded part 65, a projection 69 on its front edge, which projection is in line with a recess 70 of the grip 3, adjacent the trigger guard 9.

Common means for locking said bar 35 40 and the trigger 29 against movement, is provided and in this instance comprises a safety member round in cross section, rotatably carried by the hand grip 3, adjacent the trigger guard 9, and provided with 45 diametrically opposite circumferential cut-away portions 72, 72. When the safety member 71 is turned to a position so as to bring the recesses 72, 72 in line with the path of travel of the trigger 29 and the projection 69, said trigger may be moved rearward into the corresponding recess 72, and the projection 69 may be moved into the other recess 72; and conversely, when the rotatable member 71 is moved so as to bring 50 said recesses out of register with the trigger and projection 69, it will be impossible to move said trigger and projection.

The operation of the mechanism of my pistol is as follows:

60 Assuming the parts to be in the cocked position shown in Figure 1 and the safety 34 rocked out of engagement with the finger 33 of the sear by the act of the shooter firmly grasping the hand grip 3 and pressing 65 upon the projection 68 and the portion

67 of the safety bar 35, pressure upon the trigger 29 will move the same upward upon its pivot 30, thereby simultaneously raising the bell crank lever 27 and consequently 70 rocking upward the sear arm 25, which tilts the catch arm 40 of the sear upward, disengaging the hook 41 thereof from the projection 21 of the firing-pin barrel 22. The firing-pin driving spring 39 now functions to drive the firing-pin forward to penetrate 75 the cartridge primer, thus exploding the cartridge, or shell. Recoil now ensues consequent upon the explosion, driving the barrel 1 and the barrel extension 2 and breech block 12, with the parts contained therein, 80 rearward three-eighths of an inch. The breech block 12, at the beginning of this recoil movement, is firmly locked against the rear of the barrel by being wedged in front of the lugs 23 of the barrel extension 85 shell 2'. As said, the barrel, the barrel extension and breech block move back together three-eighths of an inch until the projection 8, carried by the barrel extension 2, contacts with the shoulder 7 of the portion 90 5 of the receiver 4, whereupon further movement rearward of said barrel and barrel extension is arrested.

During this described movement of three-eighths of an inch travel, the bell crank lever 45 is rocked on the pivot 46 so that the longer arm of said lever moves from the inclined position thereof, shown in Figure 1, to a substantially perpendicular position,—that is, a position substantially at right 95 angles to the axis of the barrel 1,—the ends of the pin 44 consequently riding out of the bottom of the recesses 43 in the breech block 12 and contacting with the walls 43' of said recesses. The continued upward pressure 100 upon said walls 43' exerts an upward stress upon the breech-block, which is consequently tilted upward so as to remove the rear lower end of the breech block out of contact with the front ends of the ribs 23, bringing the 105 bottom of the breech block in line with the top edges of said ribs. The breech block is now free to continue its recoil movement, and, since the barrel and barrel extension are locked, as stated, said breech block now 110 moves rearward under the force of recoil independent of said barrel and barrel extension, said breech block sliding upon the inclined top surfaces 24 of the ribs 23. The bell crank lever 45, by reason of the extended 115 engagement of the ends of the crosshead 44 in the rear recesses 43 of the breech block, is, during the said independent recoil movement of the breech block, thrown from the perpendicular position previously referred 120 to to the position shown in Figure 2, this figure showing the extreme rearward recoil position of the parts.

During this independent recoil movement 125 of the breech block, the bell crank lever 45 130

is swung so as to elevate the link 47 from the inclined position thereof, shown in Figure 1, to a more nearly perpendicular position, as shown in Figure 2, said link 47 swinging upon the pivot 48. Consequently, the shorter arm of the bell crank lever 45 is raised (compare Figures 1 and 2) thereby pulling upward upon the stirrup 52 and drawing the rod 54 upward, thus placing the stirrup 52 under tension of the compressed spring 57.

During said independent recoil movement of the breech block 12, the member 50, carried by the lever 45, is thrown into contact with the bridge 23' of the arms 19. As the member 50 is thrown rearward by the lever 45, the arms 19 are pulled so as to move the firing-pin tubular member 18 rearward, independently of the rearward movement of the breech block 12, thereby bringing the inclined edge of the projection 21 into contact with the inclined edge 42 of the catch 40, until the said projection passes to the rear of the lower end of said inclined edge 42, whereupon said catch 40 drops, so as to engage the hooked terminal of said catch with said projection, as shown in Figure 2, thereby compressing the firing-pin driving spring 39.

30 The parts being now in the position shown in Figure 2, the tension coil spring 57 now expands, driving the rod 54 downward, thus pulling the shorter arm of the bell crank lever 45 downward, thereby moving the link 47 from the position thereof shown in Figure 2 to the position shown in Figure 1, and consequently moving the breech block 12 forward. The breech block finally drops downward behind the lugs 23.

40 The exploded shell is removed or extracted, by any suitable mechanism, not constituting a part of this invention, such mechanism being well known in the art.

What I claim to be new is:

45 1. In a fire-arm the combination with a 110
slidable barrel and barrel extension, of a breech block within said barrel extension, ribs disposed on the inner faces of the side walls of the barrel extension and extending longitudinally thereof, the upper longitudinal edges of said ribs being inclined to the axis of the barrel, said inclined edges extending upward and rearward from the front ends of said ribs, the rear end of said breech block normally bearing against the forward ends of said ribs, and means operable at the end of the recoil movement of said barrel and barrel extension to tilt the rear end of said breech block upward, out of locking engagement with said ribs, said means including a lever loosely engaging said breech block, and a link pivoted to said lever.

50 2. In a fire-arm the combination with a 115
slidable barrel and barrel extension, of a breech block within said barrel extension, ribs disposed on the inner faces of the side walls of the barrel extension and extending longitudinally thereof, the upper longitudinal edges of said ribs being inclined to the axis of the barrel, said inclined edges extending upward and rearward from the front ends of said ribs, the rear end of said breech block normally bearing against the forward end of said ribs, and means operable at the end of the recoil movement of said barrel and barrel extension to tilt the rear end of said breech block upward, out of locking engagement with said ribs, said 120

longitudinally thereof, the upper longitudinal edges of said ribs being inclined to the axis of the barrel, said inclined edges extending upward and rearward from the front ends of said ribs, the rear end of said breech block normally bearing against the forward ends of said ribs, and means operable at the end of the recoil movement of said barrel and barrel extension to tilt the rear end of said breech block upward, out of locking engagement with said ribs, said means including a lever loosely engaging said breech block.

3. In a fire-arm the combination with a 125
slidable barrel and barrel extension, of a breech block within said barrel extension, ribs disposed on the inner faces of the side walls of the barrel extension and extending longitudinally thereof, the upper longitudinal edges of said ribs being inclined to the axis of the barrel, said inclined edges extending upward and rearward from the front ends of said ribs, the rear end of said breech block normally bearing against the forward ends of said ribs, and means operable at the end of the recoil movement of said barrel and barrel extension to tilt the rear end of said breech block upward, out of locking engagement with said ribs, said means including a lever loosely engaging said breech block.

4. In a fire-arm the combination with a 130
slidable barrel and barrel extension, of a breech block within said barrel extension, ribs disposed on the inner faces of the side walls of the barrel extension and extending longitudinally thereof, the upper longitudinal edges of said ribs being inclined to the axis of the barrel, said inclined edges extending upward and rearward from the front ends of said ribs, the rear end of said breech block normally bearing against the forward ends of said ribs, and means operable at the end of the recoil movement of said barrel and barrel extension to tilt the rear end of said breech block upward, out of locking engagement with said ribs, said means including a lever loosely engaging said breech block.

5. In a fire-arm the combination with a 135
slidable barrel and barrel extension, of a breech block within said barrel extension, ribs disposed on the inner faces of the side walls of the barrel extension and extending longitudinally thereof, the upper longitudinal edges of said ribs being inclined to the axis of the barrel, said inclined edges extending upward and rearward from the front ends of said ribs, the rear end of said breech block normally bearing against the forward end of said ribs, and means operable at the end of the recoil movement of said barrel and barrel extension to tilt the rear end of said breech block upward, out of locking engagement with said ribs, said 140

means including a lever having projections loosely engaging said breech block.

6. In a fire-arm the combination with a 5
slidable barrel and barrel extension, of a
breech block within said barrel extension,
ribs disposed on the inner faces of the side
walls of the barrel extension and extending
longitudinally thereof, the upper longitudinal
edges of said ribs being inclined to the
10 axis of the barrel, said inclined edges ex-
tending upward and rearward from the
front ends of said ribs, the rear end of said
breech block normally bearing against the
forward end of said ribs, and means operable
15 at the end of the recoil movement of said
barrel and barrel extension to tilt the rear
end of said breech block upward, out of lock-
ing engagement with said ribs, said means
including a lever carrying a pin, the ends
20 of which loosely engage said breech block.
7. In a fire-arm, the combination with a
slidable barrel and barrel extension, or a
breech block within said barrel extension, a
firing-pin structure slidably projecting with-
25 in said breech block, ribs disposed on the
inner faces of the side walls of the barrel
extension and extending longitudinally
thereof, the upper longitudinal edges of said
ribs being inclined to the axis of the barrel,
30 said inclined edges extending upward and
rearward from the front ends of said ribs,
the rear end of said breech block normally
bearing against the forward ends of said
ribs, means including a lever operable at
35 the end of the recoil movement of said bar-
rel and barrel extension to tilt the rear end
of said breech block upward, out of locking
engagement with said ribs, and a member
carried by said lever and engageable with
40 said firing-pin structure in the recoil move-
ment of the breech block to force the firing
pin structure rearward, independent of the
recoiling breech block.

8. In a fire-arm the combination with a
45 slidable barrel and barrel extension, of a
breech block within said barrel extension,
ribs disposed on the inner faces of the side
walls of the barrel extension and extending
longitudinally thereof, the upper longitudi-
50 nal edges of said ribs being inclined to the
axis of the barrel, said inclined edges ex-
tending upward and rearward from the
front ends of said ribs, the rear end of said
breech block normally bearing against the
55 forward ends of said ribs, and means oper-
able at the end of the recoil movement of
said barrel and barrel extension to tilt the
rear end of said breech block upward, out of
locking engagement with said ribs, said
60 means including a lever loosely engaging
said breech block, and spring controlled
means connected with said lever for tending
to throw the latter forward.

9. In a fire-arm the combination with a slid-
65 able barrel and barrel extension, of a breech

block within said barrel extension, ribs dis-
posed on the inner faces of the side walls of
the barrel extension and extending longitudi-
nally thereof, the upper longitudinal edges of
70 said ribs being inclined to the axis of the bar-
rel, said inclined edges extending upward
and rearward from the front ends of said
ribs, the rear end of said breech block normal-
ly bearing against the forward ends of said
75 ribs, and means operable at the end of the
recoil movement of said barrel and barrel
extension to tilt the rear end of said breech
block upward, out of locking engagement
80 with said ribs, said means including a bell
crank lever, the longer arm of which loosely
engages said breech block, and spring con-
trolled means connected with the shorter
arm of said lever and tending to throw said
lever forward.

10. In a fire-arm the combination with a 85
slidable barrel and barrel extension, of a
breech block within said barrel extension,
ribs disposed on the inner faces of the side
walls of the barrel extension and extending
longitudinally thereof, the upper longitudi-
90 nal edges of said ribs being inclined to the
axis of the barrel, said inclined edges ex-
tending upward and rearward from the
front ends of said ribs, the rear end of said
breech block normally bearing against the 95
forward ends of said ribs, and means oper-
able at the end of the recoil movement of
said barrel and barrel extension to tilt the
rear end of said breech block upward, out of
locking engagement with said ribs, said 100
means including a bell crank lever, the
longer arm of which loosely engages said
breech block, a member loosely engaging the
shorter arm of said lever, and a spring con-
trolled rod loosely engaging said member 105
and tending to throw said lever forward.

11. In a fire-arm the combination with a
slidable barrel and barrel extension, of a
breech block within said barrel extension,
ribs disposed on the inner faces of the side 110
walls of the barrel extension and extending
longitudinally thereof, the upper longitudi-
nal edges of said ribs being inclined to the
axis of the barrel, said inclined edges ex-
tending upward and rearward from the 115
front ends of said ribs, the rear end of said
breech block normally bearing against the
forward ends of said ribs, and means oper-
able at the end of the recoil movement of
said barrel and barrel extension to tilt the 120
rear end of said breech block upward, out
of locking engagement with said ribs, said
means including a lever loosely engaging
said breech block, and a pivoted link to
which said lever is pivotally secured, and 125
means for limiting the pivotal movement of
said link in one direction.

In testimony whereof I hereunto affix my
signature.

DONALD H. STEVENSON.
